MOSES HAWKINS, OF BIRMINGHAM, CONNECTICUT, ASSIGNOR TO HIMSELF, ROYAL M. BASSETT, AND THEODORE S. BASSETT, OF SAME PLACE.

Letters Patent No. 96,913, dated November 16, 1869.

IMPROVED FRICTION-CLUTCH.

The Schedule referred to in these Letters Patent and making part of the same

To all whom it may concern:

Be it known that I, MOSES HAWKINS, of Birmingham, in the county of New Haven, and State of Connecticut, have invented a new Improvement in Clutch-Pulley; and I do hereby declare the following, when taken in connection with the accompanying drawings, and the letters of reference marked thereon, to be a full, clear, and exact description of the same, and which said drawings constitute part of this specification, and represent, in—

Figure 1, a face view.

Figure 2, a side view.

Figure 3, a longitudinal central section.

Figure 4, a longitudinal central section enlarged, showing the parts in different positions.

This invention relates to an improvement in the mechanical attachment commonly known as "clutch-pulleys," that is, the arrangement of a pulley upon the driving-shaft, so that, at the pleasure of the operator, the pulley may be stopped or caused to revolve with the shaft, and in which a pulley, loose upon the shaft, its inner surface made conical, is combined with a plate, the edge of which is inclined, and so as to fit the inner surface of the pulley, the said plate arranged upon the shaft so as to revolve freely with the shaft, and yet so as to be moved longitudinally thereon, so that the said plate may be forced into the pulley, (or the pulley forced thereon, as the case may be,) the friction between the two surfaces causing the pulley to revolve with the shaft; and

The invention consists—

First, in forming upon the inner surface of the pulley, one or more spiral slots or grooves, and combined with a sliding bar upon the surface of the friction-plate, operating radially, or nearly so, so that when the said bar is forced out, it will enter the slot or groove in the pulley, and, by the inclination or spiral form of the said slot, draw the pulley on to the friction-plate, or *vice versa*, as the case may be.

Second, in the arrangement of an arm, so as to slide longitudinally upon the shaft, and combined, by means of an inclined slot, with a radial bar or bars, so that by the movement of the said arm, the said bar is drawn back or forced out positively.

Third, in the arrangement of the said arm, in combination with the friction-plate and sliding bars, so that when the bar or bars are withdrawn, the plate itself will also be drawn from the pulley, to free the pulley from the plate.

A is the driving-shaft, upon which the pulley B is arranged, so as to revolve freely thereon.

The inner surface of the said pulley is made conical, as seen in fig. 4, and a friction-plate, C, is fitted to correspond to the inner surface of the pulley, and this plate C is placed upon the shaft, and caused to revolve with the shaft, by means of a key, (see fig. 3,) but by preference, is made so that the plate may move longitudinally on the shaft.

The inner surface of the said pulley is grooved, or slots are formed therein, (here represented as slots *a*, and may be one or more in number.) These slots are formed, to a greater or less extent, around the surface of the pulley, in a spiral form.

On the plate C, I arrange one or more sliding bars, D, here represented as two, upon opposite sides, and arranged in suitable guides, so as to be moved radially upon the said plate. The sliding bars are constructed so that as they are moved outward, they will enter the slots *a*, before mentioned; that is to say, when the plate C is drawn out from the pulley, as denoted in broken lines, fig. 4, the bars will enter the lowest part of the incline or spiral slot, and as they revolve, will run along the said slot, drawing the pulley on to the plate, or the plate into the pulley, as the case may be, here represented as drawing the plate into the pulley, until the friction between the plate and the pulley becomes so great that the pulley will revolve with the plate; then, when the bars are withdrawn, the pulley is released, and will run from the friction-surface.

To operate the bars, I arrange an arm, E, for each bar upon a head, F, so as to slide longitudinally on the shaft, and yet keyed thereon, so as to revolve with the shaft.

The said arms extend toward the plate, and are provided, each with a slot, *e*, inclined, and into each of the slots a pintle, *f*, on the bars D, connects the bars D to the arm F, and the slots inclined, so that when the bars are moved in one direction, they will force their respective bars radially outward, and in the other direction, will draw them in, by preference, constructed so that by forcing the arms toward the plate, they will throw their arms outward, and *vice versa*.

By this last-named form of slots, when the arm is drawn out, as seen in fig. 4, so as to withdraw the bars D, the pintle of the bars having reached the end of the slot, the further movement of the arms will draw the plate from the pulley until arrested by a stop, *n*, on the shaft.

While I prefer to allow the longitudinal movement which I have described, to the plate C, it will be evident that the plate C may be fixed rigidly to the shaft, and the pulley allowed a slight longitudinal movement, so that the grooves in the pulley will draw the pulley on to the plate.

By this construction, the action of my clutch is positive to the fullest extent, and being constructed without springs, is not liable to the difficulties or uncertain action in clutches in which springs are employed.

I do not wish to be understood as broadly claiming the forcing of a conical surface into a pulley, for the purpose of causing the pulley to revolve in consequence

of the friction between the two surfaces, as such, I am aware, is not new; but

What I do claim as my invention, is—

1. The arrangement of the sliding bars D D on the friction-plate C, combined with the spiral grooves or slots *a* in the pulley, substantially as and for the purpose set forth.

2. In combination with the bars D on the plate, and slots or grooves *a* in the pulley, the arms E, arranged upon the shaft relative to the bars D, and so as to op-

erate the said bars substantially in the manner and for the purpose set forth.

3. In combination with the plate C and bars D arranged thereon, and operated by the arms E, the slots *e*, constructed so as to serve the double purpose of drawing in the said arms, and withdrawing the plate from the pulley, substantially as set forth.
